ARTIFICIAL KIDNEY TANK

Howard G. Healy, Hollis, N.H., assignor to
Medigenics Inc., Brooklyn, N.Y.

Filed June 23, 1971, Ser. No. 155,971

Term of patent 14 years

Int. Cl. D24—02

U.S. Cl. D83—1 F

FIG. 2

FIG. 4

FIG. 1

FIG. 3

FIG. 5

FIG. 1 is a side elevational view of my artificial kidney tank; the other side being a mirror image;

FIG. 2 is a top plan view thereof;

FIG. 3 is a bottom plan view thereof;

FIG. 4 is a front elevation thereof, with the cover member in an open position; and

FIG. 5 is a rear elevational view thereof.

I claim:

The ornamental design for an artificial kidney tank, substantially as shown and described.
